UNITED STATES PATENT OFFICE.

WILLIAM GRANNIS, OF KEWAUNEE, WISCONSIN.

CAN BODY AND TOP.

1,312,626.

Specification of Letters Patent.

Patented Aug. 12, 1919.

Application filed June 19, 1916, Serial No. 104,445. Renewed November 8, 1918. Serial No. 261,717.

To all whom it may concern:

Be it known that I, WILLIAM GRANNIS, a citizen of the United States, residing at Kewaunee, in the county of Kewaunee and State of Wisconsin, have invented certain new and useful Improvements in Can Bodies and Tops, of which the following is a specification.

This invention is an improvement on the can and top for which Letters Patent were issued to me Feb. 29, 1916, No. 1,173,422.

The object of the present invention is to provide for an absolutely tight joint at the juncture of union of the can and its removable top, and also to provide a handle for the top which will serve to lock and unlock the top, the locking means being carried by and working automatically with said handle.

In hauling milk and cream to market, either to a creamery or a shipping point the liquid in the can is splashed upwardly against the sides and top of the can. Then when the cover is removed it will run down the sides of the can, and in warm weather will sour on the exterior of the can.

But in my present invention I not only form a tight joint about the can neck and the flange of the can top, but I also, by forming a double point of contact, prevent any liquid from getting in between the top and the can neck, so that a joint is formed that will not only prevent leakage while in transit, but will prevent the dripping of any of the can contents down the outside of the can on removal of the cover.

With these various objects in view the invention consists of the novel features of construction hereinafter described, pointed out in the claim and shown in the accompanying drawings, in which:—

Figure 1 is a side elevation of the can breast with top locked in place.

Fig. 2 is a vertical cross section therethrough.

Fig. 3 is a detail sectional view through the can neck and packing.

Fig. 4 is a detail side elevation of the locking means.

In the drawing 1 designates the breast of a can the neck of which is formed by a flange 2. In said flange is a circumferential groove 3. Secured to opposite sides of the can are lugs 4, said lugs having upright portions

containing eyes 5, and notched adjacent the can neck as at 6.

Fitting around the flange 2 is a gasket, preferably of rubber 7, and said gasket has on its inner face a longitudinally extending bead 8, said bead being off and below the longitudinal center of the gasket. This gasket extends above the flange or neck of the can.

A top 9 is provided with a flange 10 adapted to fit over the said gasket and to press the bead of the gasket firmly into the groove 3, by means of a wedging action.

This top is notched at two opposite points as at 11. The gasket 7 when in position slips into the notches 6 of the lugs and the notches 11 of the top receive the lugs, and act as a guide in placing the top in place, as said top can not be otherwise fitted into position.

Lugs 12 are carried by the can top and provide bearings for a pivoted bail or handle 13. These lugs like the lugs 4 are riveted and soldered in place. They are arranged at the notched portions of the flange of the top, and are also notched, the notches of the lugs 12 and of the flange registering. But as said lugs are soldered and permanent, they may be considered as a unitary structure, thickening and strengthening the flange 10 at these points, so that in the completed device the notches of the flange 10 and of the lugs 12 are practically one, so far as appearance and mechanical function are concerned.

The bail 13 is provided with cam hooks 14 and when the bail is lifted or thrown to one side, said hooks are disengaged, but when the handle is thrown to the other side of the top the cam hooks are forced into the eyes 5 and not only lock the top to the can, but as the handle is pressed down the top is pulled down over the can neck.

The inner surface of the top adjacent the flange 10 is provided with a groove 15, and when the top is pressed down by the cam action of the hooks 14 this groove receives the upper, projecting edge of the gasket 7. A tight joint is therefore made between the can top and the upper edge of the gasket, and between the bead 8 of the gasket and the flange or neck 2 of the can.

The utility and advantages of this con-

struction will be apparent to those manufacturing and using devices of this character.

What I claim is:—

The combination with a can and top, of a
5 depending notched flange carried by the
top, vertically arranged outstanding, per-
forated lugs carried by the can and adapted

to enter from below the flange notches, a bail
carried by the top, and cam hooks carried
by the bail and adapted to enter the perfora-
tions of the lugs, after said lugs are seated
in said notches.

In testimony whereof I affix my signature.

WILLIAM GRANNIS.
